A. C. Felton Inventor { J. B. Lovsky-
Thomas Gould

United States Patent Office.

A. C. FELTON, OF BOSTON, MASSACHUSETTS.

Design No. 2,675, dated June 18, 1867.

DESIGN FOR A CLOCK-CASE.

The Schedule referred to in these Letters Patent and making part of the same.

TO ALL WHOM IT MAY CONCERN:

Be it known that I, A. C. FELTON, of Boston, in the county of Suffolk, and State of Massachusetts, have originated and produced a new Design for Pendulum-Clock Cases, of which the following is a full and clear description, reference being had to the accompanying drawing, making part of this specification.

The design relates to the ornamentation of that class of long-pendulum clocks in which the pendulum and clock movements are contained within an oblong case, which is hung upon or against a perpendicular wall, said design being shown in the accompanying photographic representation of a clock.

a denotes the case, resting upon a base, *b*, and surmounted by a cap, *c*. *o* is the door in front of the pendulum, said door having a glass panel, *d*, painted, if desirable, with any suitable figures, but having a transparent surface, *e*, directly opposite the pendulum disk, as seen at *f*, in order that the movement of the pendulum may be observed. The dial *g* is covered by a door having a glass panel, the frame *h* of this door being formed as a circular ring projecting out from the face and sides of the case, as shown in the photograph. The cap *c* is ornamented with an urn, *i*, wings *k*, and posts *l*, and with a moulding, *m*, and at the front upper and lower corners of the case are cap and base-mouldings *n*. The base has projecting cap and base-pieces *o* and *p*, and a truncated pyramidal body, *q*, with an ornament, *r*, under the piece *p*, and a moulding, *s*, resting against the wall.

I claim the design for a clock-case, as shown in the drawing.

A. C. FELTON.
